UNITED STATES PATENT OFFICE.

SAMUEL PORTER, OF DENVER, COLORADO.

BOILER-FURNACE.

SPECIFICATION forming part of Letters Patent No. 444,984, dated January 20, 1891.

Application filed April 1, 1890. Serial No. 346,161. (No model.)

To all whom it may concern:

Be it known that I, SAMUEL PORTER, of Denver, in the county of Arapahoe and State of Colorado, have invented a new and Improved Boiler-Furnace, of which the following is a full, clear, and exact description.

The object of the invention is to provide a new and improved boiler-furnace which is simple and durable in construction, utilizes the fuel to the best advantage, insures complete combustion, and consumes the smoke and gas evolved from the burning fuel.

The invention consists of a circular grate mounted to turn and a divided ash-pit arranged below the grate.

The invention also consists in certain parts and details and combinations of the same, as will be described hereinafter, and then pointed out in the claims.

Reference is to be had to the accompanying drawings, forming a part of this specification, in which similar letters of reference indicate corresponding parts in all the figures.

Figure 1 is a sectional plan view of the improvement on the line $y-y$ of Fig. 3. Fig. 2 is a transverse section of the improvement on the line $z-z$ of Fig. 3, and Fig. 3 is a sectional side elevation of the improvement on the line $x-x$ of Fig. 1.

The improved furnace A is provided with the usual brick-work B, supporting the boiler C, below which is formed, near the front end, the fire-box D, divided into two compartments by a transversely-extending water-drum E, connected by suitable pipes F with the water-compartment of the boiler. The principal use of the water-drum is to divide the furnace transversely into two compartments, the front compartment for coking the coal or fuel and the rear compartment for thorough combustion. The water-drum is placed down close to the fire, so that the gas from the front part in passing under the drum is kept down close to the brisk fire in the rear part; also, its position so close to the fire will generate steam, thereby helping the boiler. The space on top of the drum and from the boiler out to the brick-work of the sides is to be filled in solid with fire-brick or other material, so that the only passage from front to rear of the fire-box is under the water-drum.

The fire-box D is provided with a segmental

grate G, mounted to turn and located above the ash-pit H, which is also divided into two compartments by a transversely-extending wall I, connected with the sides of the brick-work B.

In the front wall of the brick-work B are arranged the fuel-doors J, opening into the fire-box D, so as to permit of introducing the fuel into the front compartment of the fire-box. A fuel-outlet door K is arranged in one of the side walls of the brick-work B, and opens into the rear compartment of the fire-box D directly above the circular grate G. The ash-pit H is provided in the front wall of the brick-work B with the doors L, leading to the front compartment of the ash-pit, and the side door N, arranged below the door K, leads to the rear compartment of the said ash-pit.

The circular grate G is preferably arranged as follows: A bevel gear-wheel G' carries in its center a downwardly-extending pin G², mounted to turn in suitable bearings in a bridge G³, secured in the brick-work B of the furnace. The bevel gear-wheel G' meshes into a bevel-pinion O, secured on a shaft O', mounted to turn in suitable bearings and extending through one side of the brick-work B to the outside, and carrying at its outer end a gear-wheel O², adapted to be driven by suitable machinery, so as to impart a rotary motion to the shaft O', which latter, by the pinion O, turns the gear-wheel G'. The latter is provided with an annular flange G⁴, traveling on friction-rollers G⁵, mounted to turn in suitable bearings in the bridge G³, so that the gear-wheel G' moves easily when rotated, as previously described, the center pin G² being relieved from all strain. The flange G⁴ supports the circular grate-bridge G⁶, supporting the series of grate-plates G⁷, which can be readily removed and replaced by new ones in case they are worn out. The rim of the grate-bridge G⁶ extends a suitable distance above the top of the plates G⁷ to prevent the fuel from falling off the latter.

It is understood that the sides of the fire-box B in that part which contains the circular grate G are made circular, so that no fuel held on the grate can fall into the ash-pit H without passing through the grate-plates G⁷. The back of the ash-pit H is formed by a

transverse wall B', extending slightly above the top of the grate G at the rear compartment of the fire-box D, which latter at this rear end connects with the space P, formed 5 between the brick-work B under the rear part of the boiler C, and leads to the space P', extending at the back end of the boiler C, so that the heat passing through the spaces P and P' from the fire-box D can pass into the 10 rear ends of the smoke-flues Q of the boiler C, and then through the same to the chimney R.

The operation is as follows: The grate G is caused to revolve in the manner previously 15 described, and in the direction of the arrow a', and after the fire is started additional fuel is passed onto the grate through the doors J. The fuel burns very slowly in the front compartment of the fire-box D, owing to the trans- 20 verse drum E, which prevents a direct draft from the spaces P and P', connected by the flues Q with the chimney R, and as this is the only space for the smoke and gases to pass through the water-drum keeps said gases and 25 smoke down close to the briskly-burning fire in the rear compartment, and they are thereby consumed. The fuel, after passing the trans- 30 verse drum E and entering the rear compartment of the fire-box D, is subjected to a heavy draft, as this rear compartment is directly 35 and openly connected with the spaces P and P', the air being introduced through the ash- 40 pit door N, located in one side of the brick- work B. The coking is all done in the front 45 part of the grate before passing the water- drum. The object of the coking in the front 50 part of the grate is to produce a gas that will burn in passing over the brisk fire in the back 55 part of the grate. (Hardly any smoke will be 60 produced. Smoke will not burn at a low temperature.) The door K is for cleaning the 65 fire, or, in other words, for removing cinders that may have caked and would not go through 70 the grate. By the time the fuel has arrived 75 at the door K it is well coked, and is removed 80 from the grate G through the side door K by 85 suitable means. Thus it will be seen that 90 the fuel in the front compartment of the fire- 95 box D burns very slowly, while in the rear 100 compartment it burns very brightly, so that 105 the coal is thoroughly coked, and the heat is 110 applied under the center of the boiler, so that 115 the water therein is rapidly converted into 120 steam. It will further be seen that as the 125 drum E, containing boiler-water, is subjected 130 to considerable heat a complete circulation 135 of the water in the boiler is established by the 140 connection of the drum E with the pipes F, leading to the water-compartment of the 145 boiler. It will further be seen that at the 150 front doors J and L the draft in the front 155 compartments of the fire-box D, as well as the 160 ash-pit H, can be controlled separately from 165 the draft in the rear compartments of the said 170 fire-box and ash-pit, in which the draft is 175 controlled by the doors N and K.

Having thus described my invention, what

I claim as new, and desire to secure by Letters Patent, is—

1. In a furnace, the combination, with a fire-box provided with a revoluble grate, of a divided ash-pit arranged below the said grate, substantially as shown and described. 70
2. In a furnace, the combination, with a grate mounted to turn, of a transversely-di- 75 vided fire-box arranged above the said grate and a similarly-divided ash-pit arranged below the said grate, substantially as shown and described. 80
3. In a boiler-furnace, the combination, with a water-drum connected with the water-compartment of the boiler, of a fire-box through which passes transversely the said water-drum, and a circular grate mounted to turn below the said fire-box, substantially as shown 85 and described. 90
4. In a boiler-furnace, the combination, with a water-drum connected with the water-compartment of the boiler, of a fire-box through which passes transversely the said water- 95 drum, a circular grate mounted to turn below the said fire-box, and doors leading to the front compartment of the said fire-box and a door leading from the rear compartment of said fire-box, substantially as shown and de- 100 scribed. 105
5. In a boiler-furnace, the combination, with a water-drum connected with the water-compartment of the boiler, of a fire-box through which passes transversely the said water- 110 drum, a circular grate mounted to turn below the said fire-box, and an ash-pit arranged below the said grate and having a transverse partition dividing the ash-pit into a front and rear compartment, substantially as shown and de- 115 scribed. 120
6. In a boiler-furnace, the combination, with a water-drum connected with the water-compartment of the boiler, of a fire-box through which passes transversely the said water- 125 drum, a circular grate mounted to turn below the said fire-box, an ash-pit arranged below the said grate and having a transverse partition dividing the ash-pit into a front and rear compartment, and doors leading to the front 130 compartment of the said ash-pit and a door leading from the rear compartment of the said ash-pit, substantially as shown and de- 135 scribed. 140
7. In a furnace, the combination, with a transversely-extending water-drum connected with the boiler, of a fire-box divided by the said drum into a front and a rear compartment, inlet and outlet doors connected with the said front and rear compartments, 145 respectively, and a circular grate mounted to turn and arranged in the bottom of the said fire-box, substantially as shown and described. 150
8. In a furnace, the combination, with a transversely-extending water-drum connected with the boiler, of a fire-box divided by the said drum into a front and a rear compartment, inlet and outlet doors connected with the said front and rear compartments, 155

respectively, a circular grate mounted to turn and arranged in the bottom of the said fire-box, and means, substantially as described, for imparting a rotary motion to the said 5 grate, as set forth.

9. In a furnace, the combination, with a transversely - extending water - drum connected with the boiler, of a fire-box divided by the said drum into a front and a rear compartment, inlet and outlet doors connected 10 with the said front and rear compartments,

respectively, a circular grate mounted to turn and arranged in the bottom of the said fire-box, and an ash-pit having a transverse partition dividing it into a front and a rear compartment, each having a door, substantially 15 as shown and described.
